UNITED STATES PATENT OFFICE.

STANWOOD E. FLICHTNER, OF ENGLEWOOD, NEW JERSEY, ASSIGNOR, BY MESNE ASSIGNMENTS, TO COOPER HEWITT ELECTRIC COMPANY, A CORPORATION OF NEW YORK.

MERCURY-PUMP.

SPECIFICATION forming part of Letters Patent No. 794,707, dated July 18, 1905.

Application filed October 23, 1902. Serial No. 128,423.

To all whom it may concern:

Be it known that I, STANWOOD E. FLICHTNER, a citizen of the United States, and a resident of Englewood, in the county of Bergen and State of New Jersey, have invented 5 certain new and useful Improvements in Mercury-Pumps, of which the following is a specification.

My invention relates to improvements in 10 mercury-pumps, particularly such as are adapted to create a vacuum of the desired degree of exhaustion in gas or vapor lamps of the well-known Hewitt type.

The invention relates to various details in 15 the construction and arrangement of a mercury-pump apparatus, all of which will be fully described in the specification which follows, and more particularly pointed out in the claims.

20 My invention is illustrated in the accompanying drawing, which is an elevation and part section of an apparatus embodying my improvement.

Referring to the drawing, 1 is a shallow 25 circular reservoir of iron having a mercury duct or trough 2 cast on it in one piece. The reservoir 1 is covered by a glass dome-shaped cover 3, and the duct 2 may also have a cover. At intervals along the duct 2 are arranged outlet-cocks, one of which is shown 30 in the drawing at 4. The cock 4 consists of a stem 4', screwed into a valve-seat 5. Upon opening the cock mercury flows from the duct or trough 2 into fall-tubes 6 7. These 35 fall-tubes are of peculiar construction and will be specifically described later on. To the fall-tubes are attached, by rubber corks and the mercury seals, a lamp 8 and a connection 8' to a mechanical air-pump, the 40 pipe leading to which is shown at 9. The long vertical portion of the fall-tube (shown at 7) ends inside a cup 10, having a flexible outlet-pipe 11, joining the cup 10 at about the middle of its length. The outlet-pipe 11 45 empties into a general catch-basin 12, to which the outlets of all the pumps lead. The catch-basin 12 is connected by an outlet-pipe 13 with an inlet-valve 14 of an air-tank

15. The valve 14 is normally held closed by a spring 17, as shown. From near the bottom of the air-tank 15 runs a pipe 16, which extends into the reservoir 1 and ends above the level of the mercury therein. Into the top of the air-tank 15 runs an air-pipe 24, the connection of which to a source of compressed-air supply 26 is controlled by an electropneumatic valve 18, operated by a set of dry batteries 19 through the medium of a diving-bell contact 21 22.

The course of the mercury is as follows: 60 From the tank 1 it flows along the duct or trough 2, through the cock 4 5, down the fall-tubes 6 7, into the cup 10, through the outlet pipe or tube 11 into the catch-basin 12 and the outlet 13. The mercury accumulates in the catch-basin 12 until it is of sufficient height above the valve 14 to overcome the action of the spring 17 and open the valve, permitting the mercury to run into the air-tank 15 and gradually filling the latter 65 until such a level is reached as is necessary to complete the circuit of the batteries 19 through the valve 18. When this happens, the valve operates and allows compressed air to enter the air-tank 15 through the pipe 70 24. This air, pressing down upon the surface of the mercury in the tank, instantly closes the valve 14 and forces the mercury through the pipe 16 up into the reservoir 1. This operation continues until the circuit of 75 the valve 18 is broken, whereupon, the supply of compressed air being interrupted, the flow of the mercury through the pipe 16 ceases. The action of the valve 18 when it is restored to the position where it shuts off the supply 80 of compressed air from the pipe 24 also opens a vent in the said pipe, thereby releasing the compressed air above the mercury in the tank 15 and allowing the column of mercury in the tube 16 to fall to the level of 85 that in the tank 15. While the compressed air has thus been forcing the mercury from the tank 15 into the reservoir 1, the pumps have continued to cause mercury to flow 90 from the reservoir and the same has collected in the catch-basin 12. Upon the removal 95

of the air-pressure, as described above, the valve 14 reopens by reason of the pressure of the accumulated mercury above the valve in the pipe leading thereto. Under the proper 5 conditions the described series of operations repeats itself, and the lamps 8 are gradually brought to the desired state of exhaustion.

The diving-bell valve 21 22 is adapted to open the valve 18 when the mercury in the 10 air-tank 15 is high and to close it when the mercury is low. The valve consists of a contact-terminal 22, passing through an insulating-packing 23 in the top or cover 45 of the tank 15, and air-tight bell or cylinder 21, 15 which projects below the level of the conductor 22, but ends above the bottom of the tube 16. When the mercury in the tank 15 rises above the bottom of the bell 21 on the outside thereof, the mercury inside the 20 bell will not rise as rapidly, owing to the air confined within the bell. Eventually, however, the mercury inside the bell will make contact with the conductor 22 and the valve 18 will be opened to turn on the air. The resulting 25 increase of pressure outside the bell 21 will force the mercury up inside the bell, continuing the contact between the mercury and the conductor 22. This contact will continue until the level of the mercury outside 30 the bell 21 descends below the lower edge of the said bell, whereupon bubbles of air will rise inside the bell, the mercury therein will flow out, the connection with the conductor 22 will be broken, the valve 18 will be closed, and the air will be shut off.

The tank 15 is provided with the top 45 for convenience in inspecting the parts within the air-tank and providing for their possible removal or renewal. The top overhangs 40 the tank and is supported by a suitable bench 46. All the valves, pipes, and contacts and also the bottom portion of the tank itself are attached to the top 45. The tank can be taken away without interfering 45 with the parts attached to the top by simply removing the screws 47 47, which join the two parts mentioned.

The valve 14, normally closed by a spring 17 and opened by the weight of the mercury 50 column resting on the valve, is an improvement over the usual valve which remains normally open and which is shut off by the back pressure of the mercury after the air is turned on. With the latter form of valve 55 the mercury is liable to spurt out through the valve-opening, often being scattered over the floor instead of being retained in the catch-basin.

At the upper end of the fall-tube are three 60 cups 40 41 42, to which connections are made by means of rubber corks, pushed far enough into the tube to allow mercury seals over the corks. The arm 6 of the tube is provided with a pocket 43, into which the mercury 65 falls before entering the tube 7. This in-

sures the mercury being fed into the tube 7 in large drops instead of being spattered into the tube in small drops. Tube 7 is peculiarly shaped, being large at its upper end and tapering slightly below the mercury-inlet to a bore .14 to .15 of an inch. This diameter is then continued five inches or more to a point about an inch or more above the height at which the mercury would stand in the tube 7 under atmospheric pressure. This is the 75 point where the falling drops coalesce and form a solid stream. As I have said, the bore .14 to .15 of an inch extends to within an inch or so of this coalescing-point and then contracts to a bore of .1 to .12 of an inch. It 80 is well known that a glass tube is not cylindrical but conical in shape, the cone being very acute. It has been found best, however, to have that portion of the fall-tube which has a bore of .1 to .12 of an inch arranged 85 with a smaller end upward, the bore becoming wider and wider as the mercury approaches the cup 10.

The terminal which co-operates through the mercury with the terminal 22 may be either 90 the tank 15 itself or the cup or bell 21. In case the tank is used for this purpose the cup or bell 21 may be of insulating material.

In order to provide an alarm or indicator to show when the air-pressure has become 95 too low for efficient action, I insert in the compressed-air-supply pipe 27 a low-pressure alarm device, the circuit-closer of which is illustrated at 25. The circuit-closer consists of a U-shaped tube having one open leg, connected to the air-supply pipe 27, and one closed leg 28. The bend of the U is filled with mercury. The latter is connected by a wire 30 with one terminal of an electric bell 31, the other terminal of the bell being connected 100 with an insulated contact-piece 32, running into the open leg of the circuit-controller 25. When the air in the supply-chamber 26 is at the proper pressure for carrying on the operations of the pumping apparatus, it affects the 105 mercury in the U-shaped tube 25 so that it rises in the closed leg thereof until the contained air in the latter is at approximately the same pressure as that in the open leg. Under these conditions the contacts can be so 110 arranged as to leave the circuit of the bell 31 open, whereas on a reduction of the pressure in the open leg below a good operative pressure the mercury may be caused to flow back 115 into the open leg sufficiently to close the circuit of the bell 31 and sound the alarm.

The improvements in fall-tube system consist in making the same separable from the lamp and the cup 10, making the fall-tube 7 perfectly straight, so that it can readily be 120 cleaned, and giving it the peculiar shape already described.

I claim as my invention—

1. In a mercury-pump, a mercury-reservoir, a mercury-circuit, and a fall-tube in- 130

- cluded in the circuit, the said fall-tube being detachable and having four different diameters at different portions of its length, the uppermost diameter being comparatively large, 5 the two next diameters being successively shortened and the lowermost diameter being larger than the contracted portion.
2. In a mercury-pump, a mercury-reservoir, a mercury-circuit and a fall-tube included in the circuit, the said fall-tube being detachable, and being flaring at each end.

3. In a mercury-pump, a mercury-reservoir, a mercury-circuit and a fall-tube included in the circuit, the said fall-tube being flaring at its opposite ends. 15

Signed at New York, in the county of New York and State of New York, this 20th day of October, A. D. 1902.

STANWOOD E. FLICHTNER.
